(57) **CLAIM**

The ornamental design for a “portable terminal case,” as shown and described.

DESCRIPTION

FIG. 1 is a perspective view of portable terminal case showing my new design;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof;

FIG. 8 is another right side view; and,

FIG. 9 is a right view show in an open position.

The broken lines in the upper half represent a portable terminal. The broken lines form no part of the claim.
